DESIGN FOR A PLATE OR SIMILAR ARTICLE

Raymond H. Hammer, Youngstown, Ohio

Application October 25, 1934, Serial No. 53,761

Term of patent 7 years

To all whom it may concern:

Be it known that I, Raymond H. Hammer, a citizen of the United States, residing at Youngstown, in the county of Mahoning and State of Ohio, have invented a new, original, and ornamental Design for a Plate or Similar Article, of which the following is a specification, reference being had to the accompanying drawing, forming part thereof.

Fig. 1 is a plan view of a plate or similar article showing my new design; and

Fig. 2 is an elevation section of the plate or similar article shown in Fig. 1, on the line 2—2 thereof.

I claim:

The ornamental design for a plate or similar article, as shown.

RAYMOND H. HAMMER.
